(57) **CLAIM**

The ornamental design for a rear combination lamp for an automobile, as shown and described.

DESCRIPTION

FIG. 1 is a front perspective view of a rear combination lamp for an automobile of our new design;

FIG. 2 is a front view thereof;

FIG. 3 is a top plan view thereof; and,

FIG. 4 is a right side view thereof.

My design includes the mirror image of the design depicted.
